UNITED STATES PATENT OFFICE.

SEBASTIAN ZIANI DE FERRANTI, OF LONDON, ENGLAND.

COMPRESSION OF ELASTIC FLUIDS.

No. 832,784.

Specification of Letters Patent.

Patented Oct. 9, 1906.

Original application filed October 19, 1903, Serial No. 177,703. Divided and this application filed July 21, 1904. Serial No. 217,549.

To all whom it may concern:

Be it known that I, SEBASTIAN ZIANI DE FERRANTI, a subject of the King of Great Britain and Ireland, residing at 31 Lyndhurst road, London, N. W., England, have invented certain new and useful Improvements in and Relating to the Compression of Elastic Fluids, of which the following is a specification.

10 The invention relates to elastic-fluid compressors of the type described in my application, Serial No. 177,703, filed October 19, 1903, in which pistons or plugs of liquid are shot into tubes at a high velocity, thereby 15 entraining and compressing elastic fluid.

The object of the present invention is to provide means for absorbing the energy of the compressing liquid at certain points of the cycle, thereby doing work and insuring a 20 high efficiency of the complete installation.

My invention consists in the features and combination and arrangement of parts hereinafter described, and particularly pointed out in the claims.

25 Referring to the accompanying drawings, Figures 1 and 2 show forms of the invention in which a turbine-wheel is utilized to absorb the energy of the compressing liquid as it leaves the separating-chamber. Fig. 3

30 shows another form in which the turbine-wheel is placed within the separating-chamber, while Figs. 4, 5, and 6 show forms in which the compressing liquid passes directly at considerable velocity from the separating-chamber to the centrifugal pump. Fig. 7 is 35 a detail view of part of a Pelton wheel to show the construction of the bucket.

The invention will be described as applied to the compression of air by water as the 40 compressing medium.

In carrying the invention into effect according to the form shown in Figs. 1 and 2 the water enters the centrifugal thrower *b* by way of the pipe *v* and passing at high velocity through the nozzles *d* of the thrower is shot into the compressing-tubes *a* in the form of plugs, thereby entraining air and carrying it into the first separating-chamber *f*, whence pipes *h* lead to the additional separating-chamber *i*. A pipe *o* takes the compressed air from this separator to any suitable reservoir.

In order to remove the water from the separator *i* without loss of energy, a discharge-pipe *s*, provided with a suitable nozzle, causes the water to impinge on a Pelton wheel *r* or other suitable prime mover, this wheel being conveniently mounted on the same shaft as the driving-motor *t* and thrower *b*; but it may be connected by any suitable gearing. 55 The discharge from the Pelton wheel *r* is led away either by the pipe *u* to a cooling-pond or other cooler, whence it is returned to the thrower *b* through the pipe *v* (see Fig. 1) or else it is thrown away through the pipe *u'*, 60 (see Fig. 2,) fresh liquid being supplied to the thrower through the pipe *v*.

In Fig. 3 a modification is shown in which the auxiliary turbine or the like is arranged within the separating-chamber. In the general arrangement of apparatus shown the centrifugal thrower-spindle *w* is arranged vertically, an electric motor *x* being conveniently mounted on a prolongation of this spindle. The compressing-tubes *a* deliver 75 into the separator-chamber *z* and may be arranged, as shown, to pass through the jacket 2, surrounding this chamber, the cooling water in this jacket being constantly renewed in any convenient manner in order to prevent rise of temperature during compression. The compressed air passes from the separator-chamber by way of the pipe 3. The jets discharging from the compression-tubes *a* impinge upon an impact wheel or turbine 4, so 80 as to cause rotation, and this power is utilized, as shown, to aid in driving the centrifugal pump or thrower. The turbine itself in this case also acts as an efficient means of separating the air and liquid. The compressing-water passes from the separator-chamber *z* back to the pump or thrower *b* and is used over again to compress a further quantity of air. 85

In carrying the invention into effect according to another form I provide a number of fixed tubes 5, as before, into which I discharge (see Figs. 4 and 5) liquid at considerable velocity by means of a rotating piece carrying a suitable number of nozzles 9, rotating within a casing 10. The revolving nozzles may be driven in any convenient manner—as, for instance, by a belt engaging with the pulley 11—or the nozzles themselves 90 100

may be inclined, so as to assist the rotation by reaction. A series of liquid pistons is thus discharged into the tubes which may be either parallel or expanding, according to the 5 quantity of air entrained, the tubes 5 delivering into a separating-chamber 12, whence the liquid passes to a centrifugal pump or liquid-thrower 13 to have its velocity restored. In this manner no energy is lost to the cycle 10 as the liquid leaves the separating-chamber. The liquid then returns by way of the pipe 14 to the rotating nozzles, thus completing the cycle. A cooler 15 is arranged at any convenient point in the circuit to prevent undue 15 rise of temperature of the compressing liquid. Instead of employing a rotating nozzle, I may, as shown in Fig. 6, use a nozzle 16, adapted to receive an oscillating motion from any suitable gearing, such as 17. The nozzle 20 will then pass to and fro across the ends of the compressing-tubes 5, causing alternate pistons or plugs of air and water to pass down the tubes, as in the last form described. The other reference-characters on Fig. 6 bear the 25 same significance as in Fig. 4 above, the liquid, as before, passing from the separating-chamber 12 to the pump 13, so as to conserve energy to the cycle.

In all cases the compression-tubes must be 30 arranged of such length as to contain a sufficient number of liquid-pistons to preclude any possibility of air and liquid blowing back from the separating-chamber.

Having thus described my invention, what 35 I claim as new, and desire to secure by Letters Patent, is—

1. In an elastic-fluid compressor employing a liquid as the medium of compression, the combination of a plurality of tubes or 40 ducts having open ends, means for producing one or more high-velocity streams of liquid to enter the tubes, means for producing relative motion between said streams and said open ends presented to them, means for receiving 45 the compressed elastic fluid, means for employing energy in the compressing liquid not utilized directly in compressing elastic fluid, substantially as described.

2. In combination in an elastic-fluid compressor employing liquid as the medium of compression, a plurality of ducts through which elastic fluid is successively compressed by separate moving plugs of liquid; means for giving velocity to said separate plugs, a 55 receiving-chamber into which said ducts discharge together with a motor receiving energy from the compressing liquid said motor acting to assist in the work of compression by driving the velocity-imparting means, 60 substantially as described.

3. In combination in an elastic-fluid compressor employing liquid as the medium of compression, means for giving the liquid ve-

locity, means receiving energy from the compressing liquid augmenting said first-mentioned means; a plurality of ducts through which the elastic fluid is successively compressed together with a receiving-chamber into which said ducts discharge, substantially as described. 65

4. In combination in an elastic-fluid compressor employing liquid as the medium of compression, means for giving velocity to the liquid; a plurality of ducts through which the elastic fluid is successively compressed; a receiving-chamber into which said ducts discharge together with a turbine driven by the compressing liquid and acting to augment 70 said velocity-giving means, substantially as described. 75

5. An elastic-fluid compressor employing a liquid as the medium of compression, comprising centrifugal means for giving the liquid the required velocity, means for receiving the elastic fluid together with the liquid from 85 said centrifugal means to effect compression of the fluid, a separator and means for obtaining work from the discharge liquid, said means acting to augment the centrifugal means and give velocity to the liquid, substantially as described. 90

6. An elastic-fluid compressor employing a liquid as the medium of compression, comprising centrifugal means for giving the liquid the required velocity, means for receiving 95 the elastic fluid together with the liquid from said centrifugal means to effect compression of the fluid, a separator, a cooler and means for obtaining work from the discharge liquid, said means acting to augment the pump and give 100 velocity to the liquid, substantially as described.

7. An elastic-fluid compressor employing a liquid as the medium of compression comprising centrifugal means for giving the liquid the required velocity, means for receiving the liquid from said centrifugal means in the form of separate liquid traveling pistons, together with the elastic fluid a separator, and means for obtaining work from the discharge 105 liquid, said means acting to augment the pump and give velocity to the liquid, substantially as described. 110

8. An elastic-fluid compressor employing a liquid as the medium of compression comprising centrifugal means for giving the liquid the required velocity, means for receiving the liquid from said centrifugal means in separate liquid traveling pistons, together with the elastic fluid, a separator, a cooler and means for obtaining work from the discharge liquid, said means acting to augment the pump and give velocity to the liquid, substantially as described. 115

9. An elastic-fluid compressor employing a 120 liquid as the medium of compression com-

prising centrifugal means for giving the liquid the required velocity, a receiver with a connection to said centrifugal means to entrain air for compression, a turbine, a connection from said receiver to said turbine, said connection having its discharge directed to augment the power of said centrifugal means by utilizing the energy of said liquid

issuing from said receiver, substantially as described.

In witness whereof I have hereunto set my hand in presence of two witnesses.

SEBASTIAN ZIANI DE FERRANTI.
